TOOTHBRUSH CABINET

Filed Nov. 17, 1928

By Cadrow & Co.
Attorneys.

UNITED STATES PATENT OFFICE

WILLIAM HOBERT RICKLES, OF MARSHALL, TEXAS

TOOTHBRUSH CABINET

Application filed November 17, 1928. Serial No. 320,194.

The present invention has reference to a cabinet, and more particularly a cabinet for toilet use, the primary object of the invention being to provide a cabinet especially designed for containing toothbrushes or the like.

Another important object of the invention is to provide a cabinet which will permit of a circulation of air therethrough so that the 10 brushes held in the cabinet may dry.

A further object of the invention is the provision of a partitioning member for holding the toothbrushes in spaced relation with each other while supported within the 15 cabinet.

The invention again has as its object the providing of a container for toothbrushes, where they are hidden from view and are yet easily accessible to the users thereof.

With the foregoing and other objects in view which will appear as the description proceeds, the invention resides in the combination and arrangement of parts and in the details of construction hereinafter described 25 and claimed, it being understood that changes in the precise embodiment of the invention herein disclosed, may be made within the scope of what is claimed, without departing from the spirit of the invention.

Referring to the drawing:

Figure 1 is a front elevational view of a cabinet constructed in accordance with the invention.

Figure 2 is a sectional view taken on line 35 2-2 of Figure 1.

Figure 3 is a transverse sectional view through the cabinet.

Referring to the drawing in detail, the device includes a body portion which is box-like in formation, the same being shallow, but 40 sufficiently deep to permit toothbrushes to be held therein in such a way that they will not contact with the hinged closure of the device.

The body portion is formed preferably of 45 sheet metal and embodies a length of sheet metal 5 that constitutes the back of the cabinet, the side edges of the length of sheet metal being bent at right angles providing the sides of the cabinet, which are indicated by the 50 reference character 6.

One end of the length of sheet metal of which the back of the cabinet is formed, has its corners cut away and curved as at 7, lending a pleasing appearance to the cabinet. The edges of the sides 6 are turned inwardly as 55 at 8 to reinforce the sides and insure a strong and durable cabinet.

The ends of the sides, as well as the lower end of the back of the cabinet are turned inwardly at 9 reinforcing the sides and back at 60 the lower ends. Connecting the sides 6 of the cabinet at points adjacent to the lower ends thereof, is a rod 10 that holds the lower ends of the sides against movement with respect to each other and provides an open 65 ended cabinet to permit air to pass upwardly into the cabinet.

Spaced from the upper end of the back 5, is a length of sheet metal 11 which has its 70 ends soldered to the sides, the length of sheet metal 11 constituting the top of the cabinet.

As clearly shown by Figure 2 of the drawing, a portion of the length of sheet metal or top of the cabinet, indicated at 11, extends inwardly as at 12 and has its inner edge bent rearwardly at 13 to contact with the back 5 of the cabinet, supporting the lower edge of the portion 12 in spaced relation with the back where it is supplied with hooks 14 that extend outwardly therefrom in such a way 80 that toothbrushes held by the hooks 14, will be supported in spaced relation with the back 5 providing an air space at the rear of the brushes.

Positioned within the cabinet is a dividing 85 member 15 which is in the form of a rod bent to provide offsets 16, the rod being soldered or otherwise secured within the cabinet at a point substantially intermediate the top and bottom thereof. These offsets 16 define 90 compartments to receive the toothbrushes the widths of the offsets being slightly greater than the widths of the toothbrushes so that the toothbrushes will readily fit therein.

Hingedly connected to the top 11 is a cover or closure 17 which has lateral flanges 18 that embrace portions of the sides of the cabinet when the closure is moved to its closed position. Elongated openings 19 are formed in 100

the closure 17 by stamping out portions of the metal, the stamped out portions being indicated at 20.

5 A handle 21 is secured to the cover or closure 17 so that the closure may be readily lifted to gain access to the interior of the cabinet to remove a toothbrush.

10 Ventilating openings 22 are formed in the sides of the cabinet so that air passing through the openings 19 may circulate around the brushes held in the cabinet and pass outwardly through the openings 22. It is of course understood that air will also enter the cabinet through the open bottom.

15 From the foregoing it will be seen that brushes supported in the cabinet will be held in spaced relation with each other at all times, and because of the construction of the cabinet a circulation of air through the cabinet will cause the brushes to dry out quickly.

20 I claim:

25 A cabinet of the class described including a box-like body portion having an open bottom, a top wall forming a part of the body portion, a portion of the top wall extending into the body portion and being inclined inwardly, the lower end of the inclined portion being disposed in spaced relation with the back of the body portion, hooks on the inclined portion, means for preventing lateral movement of the brushes held in the body portion, and a cover for the body portion.

30 In testimony that I claim the foregoing as my own, I have hereto affixed my signature.

35 WILLIAM HOBERT RICKLES.
